Inventor:

Andrew J. Ritter

UNITED STATES PATENT OFFICE.

ANDREW J. RITTER, OF Rahway, NEW JERSEY.

IMPROVEMENT IN CARRIAGE-SEATS.

Specification forming part of Letters Patent No. **39,677**, dated August 25, 1863; antedated June 12, 1862.

To all whom it may concern:

Be it known that I, ANDREW J. RITTER, of Rahway, in the county of Union, in the State of New Jersey, have invented a new and Improved Mode of Producing an Extra Seat for Vehicles; and I do hereby declare that the following is a full and exact description thereof, reference being had to the accompanying drawings, and to the letters of reference marked thereon.

The nature of my invention consists in converting the front part of the seat-rail or handle into a movable brace and attaching the movable part of the handle to the fall or seat board in such a manner as to produce an extra seat to vehicles in a moment's time.

To enable others skilled in the art of attaching seats to vehicles to make and use my improved arrangement for seats, I will describe it in the following specification and drawings annexed thereto, which form a part of the same, reference being had to the letters and figures marked thereon.

The same letters refer to the same parts in all of the drawings.

Instead of making the rail A in one single piece from the back of the seat to the front on the rocker H, as is shown on the back seat, E, at A, Fig. 1, I make it in two pieces, *a* A, jointing them at the post B, as shown at F, Figs. 1, 2, and 3. I then take the fall or seat board C and place it in a perpendicular position in front of the seat D, and then, instead of fastening the end of the movable rail *a* to the rocker H, as is ordinarily done, I fasten it to the end of the fall or seat board C, as shown at Fig. 2, the rail *a* A still keeping its original appearance.

On the back of the fall or seat board C are the folding and supporting legs I I, which are attached to the under side of the fall or seat board C, to keep the seat up when in its horizontal position, the front being trimmed to represent a fall when perpendicular and a cushion when horizontal. Now, when an extra seat is required, it is only necessary to raise the board C to its horizontal position and drop the legs to their proper place. By this operation the movable part of the seat-rail is converted into a firm brace, and the fall-board into a substantial seat, as is shown at Fig. 3. When the seat is to be dispensed with, fold up the legs I I. Let it drop to its proper place in front of seat D by its own gravity, where it is always ready for use, as shown at Figs. 1 and 2.

What I do claim as my invention, and desire to secure by Letters Patent, is—

1. Dividing and jointing the seat-rail A and converting the front part of the seat-rail A into a movable brace, for the purpose of supporting and working the seat-board C, as hereinbefore set forth.

2. The combination of the movable front rail A with the fall or seat board C, and the supporting-legs I I, attached to the under side of the fall or seat board C, as and for the purpose herein set forth and described.

In testimony whereof I do hereby subscribe my name this the 29th day of March, 1861.

ANDREW J. RITTER.

In presence of—

GILBERT C. RITTER,
ISAAC S. MILLER.
